LIFE PRESERVER

Harold R. Tregilgas, South St. Paul, Minn.

Application August 27, 1942, Serial No. 456,329

11 Claims. (Cl. 9—17)

My invention relates to an improvement in life preservers, and deals more particularly in a type of life preserver which may be used by a person passing through a burning film of oil, and which also may be used to protect the occupant against injury by fish.

When a boat loaded with oil, gasoline, or any inflammable material which is lighter than water, sinks at sea, there is a great likelihood of the inflammable material catching on fire. It is extremely difficult for the persons on board the boat to escape from the burning area without swimming below the surface of the water for a considerable distance. It is with this problem in mind that the present life preserver has been designed.

It is the object of the present invention to provide a life preserver which will protect the occupant from surrounding flames and which will permit the occupant to move through the water covered by flaming material until an area outside of the burning area is reached. As a result a person upon a burning boat surrounded by water covered with an inflammable material may escape without travelling beneath the surface of the water.

An object of the present invention is to provide a life preserver capable of extinguishing the flame within a confined area and which will permit a person to remain in this confined area until the fire is extinguished, or until a non-flaming area is reached. This I accomplish by providing a life preserver having an opening therethrough and by providing a cover for this opening which acts to smother the flame in the area confined by the life preserver. By subsequently opening this cover air is permitted to enter the enclosure and the cover provides a wall to protect the occupant from the surrounding flames.

A feature of the present invention lies in the provision of a life preserver having an opening therethrough through which a portion of the body of the occupant may extend and having the encircling wall extending upwardly from the life preserver to guard the portion of the body of the occupant extending through the life preserver from encircling flames.

A further feature of the present invention lies in the provision of a skirt which encircles the life preserver and which widens the area about the life preserver in which flames do not exist. This skirt is designed to extend on the surface of the water encircling the life preserver and to smother the flame throughout the area encircling the life pre-

server to hold the flames at a distance from the upwardly projecting wall.

A further feature of the present invention lies in the provision of a simple and effective means of erecting the wall of the life preserver. A pair of levers are pivoted to opposite sides of the life preserver and extend within or are attached to the walls of the same. By pivoting these levers the walls of the life preserver may be erected and may be held in an erect position to guard the occupant.

A further feature of the present invention lies in the provision of a sling connecting the ends of the pivoted levers. This sling is formed of flexible material and may be used to provide a seat for the occupant of the life preserver. Simultaneously the sling provides a means of holding the walls erect and when the weight of the occupant of the life preserver is upon the sling the walls are held erect.

A further feature of the invention includes a rope or other flexible means connected to the life preserver in such a manner that the person to occupy the same may jump into the water and guide himself into the life preserver from the lower side thereof so that he may be guided into the interior of the life preserver.

A further feature of the present invention lies in the provision of windows in the wall so that the occupant of the life preserver may see in which direction to travel to escape from the flames.

A further feature of the invention lies in the provision of a means of holding the walls in closed position until they are opened from within. A suitable clip is provided to hold the walls closed and means is provided to automatically remove the clip as the walls are erected.

A further important feature of the invention lies in the provision of suitable spray means capable of introducing a spray of water either upon the life preserver or upon the occupant thereof. This spray assists in preventing the life preserver from becoming charred by the flames, helps to reduce the high temperature, and also assists in maintaining the proper oxygen content within the walls of the life preserver.

I have found that persons supported by life preservers on the surface of the ocean are often injured by certain types of fish existing in the water. In order to prevent danger of attack by such fish I form the walls of the life preserver of sufficient height so that the occupant may invert the life preserver and use the walls as the guard for feet or legs. In preferred form the

side wall is folded to provide a downwardly extending cuff in the normal use of the life preserver, which provides a double thickness wall throughout most of the height thereof to guard against the flames. When the occupant of the life preserver is out of the flaming area, this cuff can be unfolded so as to provide an elongated sleeve secured to the life preserver. A draw string is provided at the extremity of this sleeve so that a sack or bag is formed which is closed at its lower extremity. When the life preserver is inverted the occupant can be positioned in this depending sack, providing more comfort for the occupant and minimizing the danger of attack by fish.

These and other objects and novel features of my invention will be more clearly and fully set forth in the following specification and claims.

In the drawings forming a part of my specification:

Figure 1 is a perspective view of the life preserver in closed position as it would appear resting upon the surface of the water.

Figure 2 is a view similar to Figure 1 showing the life preserver in erected position.

Figure 3 is a vertical sectional view through the life preserver and the erected walls thereof.

Figure 4 illustrates in perspective the life preserver in inverted position with the lower end of the walls tied together to form a sack or bag.

Figure 5 is a vertical section through the life preserver in inverted position before the draw string is tightened to close the lower end thereof.

Figure 6 is a sectional view through a portion of the wall of the life preserver showing a portion of one of the levers used to erect the same.

Figure 7 is a view similar to Figure 6 showing the wall and lever in partially erected position.

Figure 8 is a sectional view through a pocket in the life preserver used to contain a gas mask or the like.

The life preserver includes a circular ring of cork 10, or other buoyant material covered with a suitable covering 11. This covering 11 is preferably water proof and fire proof. The members 10 and 11 may comprise a circular life preserver, such as is in common use at the present time.

Marginally secured at 12 to the buoyant body A comprising the buoyant material 10 and the covering 11 I provide a sleeve 13 of water resistant and fire-proof material, such as fire-proof duck, or the like. This sleeve 13 is flexible and in closed position may fold downwardly into a hollow mound such as is illustrated in Figure 1 of the drawings. A spring clip 14 may be provided to encircle the upper extremity of the sleeve 13 in collapsed position thereof so as to hold the sleeve closed at its upper extremity. A chain or cord 15 connects the spring clip with one of the sleeve erecting levers which will be described in detail.

A pair of opposed levers 16 are pivoted at 17 to the exterior surface of the ring-shaped life preserver A. These levers 16 extend within the sleeve 13 and are preferably hinged at 19 so that the upper portion of the levers 20 may assume an angle with respect to the main portion of the levers 16. This hinge 19 is provided so that the upper portions 20 of the lever 16 may extend in parallel relationship, as illustrated in Figure 1 of the drawings, when the sleeve is in closed position. As will be noted in Figures 6 and 7 of the drawings, however, the hinge 19 is arranged so that shoulders 21 and 22 on the lever portions

16 and 20 may abut when the two portions 16 and 20 are in alignment.

The levers 16 project beyond the pivot 17 to form hand ends 23 which depend below the surface of the water in normal position of the life preserver. These ends 23 are connected by a cord or belt 24 which provides a sling on which the occupant of the life preserver may rest while passing through flaming waters. This rope or belt 24 forms a sling on which the occupant may sit or stand while partially projecting through the life preserver A. The weight of the occupant upon the sling 24 tends to draw the lower ends 23 of the lever 16 together, thus erecting the sleeve 13 as best illustrated in Figure 2 of the drawings. The chain 15 may be connected to the end 23 of one of the levers 16 so that as the lever 23 is pulled downwardly the chain 15 will pull the clip from the top of the life preserver to allow the same to open up into erected position.

A skirt 25 is secured at 12 to the life preserver A and to the sleeve 13. This skirt is designed to lay upon the water encircling the life preserver and to provide an area encircling the life preserver where no flames will exist. This skirt thus acts to space the flames from the life preserver and to prevent injury thereto by the heat of the flames.

A pair of ropes or cords 26 are secured to opposite sides of the life preserver and these cords 26 are connected to a single cord 27. This cord 27 may be provided with a spring 28 if desired, and a handle 30 which may be grasped by the person to occupy the life preserver while jumping from the ship. The cord 27 is of sufficient length to permit the person to occupy the life preserver to hold the cord while jumping into the water, this cord or line 27 forming a guide in entering the life preserver from below the surface of the water. This spring may be provided to cushion the pull upon the life preserver as the person to occupy the same jumps from the ship.

Windows 31, formed of heat resistant material such as mica are provided in the sleeve 13 so that the occupant of the life preserver may see in which direction to travel while the sleeve 13 is erected. These windows are so positioned that the occupant may see through the same while only his head is projecting from the water. The water will thus provide a considerable protection for the body while travelling through the flaming area.

In order to keep the life preserver dampened and to prevent injury thereto by charring, I provide a pair of flexible tubes 32 and 33 which extend along the inner wall of the sleeve 13 and which extend down into the water. Bulbs or pumps 34 and 35 respectively are provided on the lower ends of the tubes 32 and 33, and spray heads 36 and 37 are provided on the upper ends thereof. The spray head 37 is directed upwardly so as to dampen the surface of the life preserver when water is forced through the tube 32 by the bulb 34. The spray head 37 may be turned downwardly so as to direct a downward spray of liquid into the interior of the life preserver when water is forced through the tube 33 by the bulb 35. The spray of water not only prevents injury to the life preserver and to its occupant and helps to cool off the air and the occupant, but also raises the oxygen content within the sleeve 13.

A water-proof pocket 39 may be provided on the interior surface of the sleeve 13 to contain a gas mask if it is so desired. This gas mask may be used while travelling through the flaming area

to prevent the consumption of carbon monoxide. An oxygen source for breathing may also be provided, if it is so desired. A pocket 39 is shown with a double closure 40 and 41 to effectively seal the contents from moisture.

Folded within the sleeve 13 and forming an extension of this sleeve I provide a cuff 42. This cuff 42 is merely the upper end of the sleeve 13 folded down into the interior of the chamber formed by erecting the sleeve 13. This cuff 42 serves the double purpose of providing a double wall to protect the occupant of the life preserver when the wall is erected, and to provide an elongation for the sleeve 13 when the life preserver is inverted. After the occupant of the life preserver has passed through the flaming area the cuff 42 is unfolded so as to extend upwardly, extending beyond the wall 13. A hem is formed as indicated at 43 in the marginal edge of the cuff 42 and a draw string 44 is provided within this hem. By pulling upon the draw string 44 the end of the cuff 42 may be closed as illustrated in Figure 4 of the drawings and the life preserver may be inverted. The occupant may then climb into the interior of the life preserver, the sleeve 13 and the extension cuff 42 forming a sack to contain the body of the occupant. This will make the life preserver more comfortable for the occupant, and at the same time will decrease the danger from fish which would be less likely to attack the depending sack than the legs or feet of the occupant.

The life preserver is maintained in the closed position illustrated in Figure 1 of the drawings until required for use. It is then tossed upon the surface of the water, floating in the position shown in Figure 1. While holding the handle 30 on the line 27 the prospective occupant jumps into the water, and using the lines 27 and 26 as guides enters the interior of the closed life preserver. By pulling downwardly on the sling 24 or pulling inwardly on the levers 23 the sleeve 13 is erected into the position shown in Figure 2. The occupant may then rest upon the sling 24 and use his arms to paddle out of the flaming area.

When once out of the flaming area the cuff 42 is unfolded into alignment with the sleeve 13 and the draw string 44 is tightened, closing the upper extremity of the wall thus formed. The life preserver is then inverted and the interior forms a support for the body of the occupant.

In accordance with the patent statutes, I have described the principles of construction and operation of my life preserver, and while I have endeavored to set forth the best embodiments thereof, I desire to have it understood that obvious changes may be made within the scope of the following claims without departing from the spirit of my invention.

I claim:

1. A life preserver comprising a buoyant body having an unclosed opening therethrough, and a peripheral open ended flexible sleeve secured to said body encircling said opening, and removable spring clip means engageable about said sleeve to hold the sleeve end tightly bunched together.

2. A life preserver comprising a buoyant body having an unclosed opening therethrough, a

sleeve having open ends secured to said buoyant body encircling said opening, and means secured to said buoyant body for holding said sleeve erect.

3. A life preserver comprising a buoyant body having an opening therethrough, a sleeve having open ends secured at one end to said body encircling said opening, and a skirt secured to said body to encircle the same and extend outwardly therefrom, said skirt comprising a ring of fabric.

4. A life preserver comprising a buoyant body having an opening therethrough accessible from one side of said body, a sleeve secured to the other side of said buoyant body encircling said opening, said sleeve being formed of flexible water resistant material and foldable from a closed position in which the free end of said sleeve is tightly bunched together and said opening is covered to an erected position in which the sleeve is open at the top.

5. A life preserver including a buoyant body having an opening therethrough, an open ended sleeve secured at its lower end to said body, and angularly spaced pairs of lever means pivotally secured to said body and to said sleeve for urging said sleeve into erected position extending upwardly from said body.

6. A life preserver comprising a buoyant body having an opening therethrough, a sleeve of flexible material secured to said body encircling said opening, a pair of levers secured to said body in opposed relation engaging said sleeve to erect the same from said body, and a sling connecting the lower ends of said levers.

7. A life preserver comprising a buoyant body having an opening therethrough, a sleeve of flexible material having open ends secured to said body encircling said opening, and opposed pairs of levers secured to said body in opposed relation and engaging said sleeve to erect the same from said body.

8. A life preserver comprising a buoyant body having an opening therethrough, a flexible sleeve secured to said body encircling said opening and designed to extend upwardly therefrom, and spray means on said body through which water may be sprayed.

9. A life preserver including a buoyant body having an unclosed opening therethrough, a sleeve having open ends secured at one end to said body about said opening, and means for drawing the other end of said sleeve together to bunch the sleeve end compactly and to form a sack secured to said body.

10. A life preserver having a buoyant body having an opening therethrough, a sleeve secured at one end to said buoyant body, and lever means for erecting said sleeve with respect to said body, said lever means including a hinged extremity, and means for limiting the pivotal movement of said hinged extremity with respect to said lever means.

11. A life preserver including a buoyant body having an unclosed opening therethrough, a flexible open ended sleeve terminally secured to said buoyant body encircling said opening, means holding said sleeve normally closed, and means for erecting said sleeve with respect to said body.

HAROLD R. TREGILGAS.
